Patent expires May 7, 1962

11 Claims. (Cl. 89—1.7)

1

The present invention relates to ordnance and has for its general object to improve the performance of guns or like projectors for projectiles, shells or bullets, such as mortars or rifles, in relation to their weight.

As normally constructed the combustion of the propellant in the chamber of a gun gives rise to a sudden and very great rise in pressure immediately after the moment of ignition, followed by a more or less rapid fall of pressure as the projectile moves along the barrel, the pressure being at a minimum when the projectile reaches the muzzle. Consequently beyond a certain point any addition to the length of the muzzle will not add sufficiently to the range to justify the extra weight and loss of mobility of the gun resulting from the increase of length.

Furthermore, as guns are normally constructed the breech chamber and barrel have to be of very heavy construction in order to withstand the great stresses due to the very high maximum pressure in the gun chamber on explosion. Consequently the gun as a whole becomes very heavy.

One object of the present invention is to avoid a very great and sudden rise of pressure on explosion of the propellant charge, thereby eliminating the necessity for heavy breech and barrel construction, with consequent increased mobility of the gun and reduction in fuel consumption costs of gun transport equipment.

Another object is to produce a substantially higher mean pressure, approaching a substantially constant pressure, in the chamber and barrel, whereby any loss of performance due to the reduced maximum pressure may be compensated and even better performance than is possible with guns of normal construction may be obtained by increasing the length of the gun barrel.

The above objects are both achieved, according to the invention, by providing a gun using a cordite or like propellant whose burning rate is dependent upon pressure, the said gun comprising a barrel having a projectile-receiving portion at its rear end, a breech chamber including a cartridge space fixed to the rear end of the barrel in which an explosive propellant charge is received when the gun is loaded, the wall of the breech chamber supporting a gas discharge member having a restricted throat and an outlet open to the atmosphere, part of said breech chamber forward of the rear wall thereof and additional to the cartridge space forming a gas space of substantial volume in direct communication with both the cartridge space and the throat of said gas discharge member, said cartridge space hav-

2

ing a venting area into the gas space at least equal to the cross-sectional area of the barrel, and said gas space being so constructed and arranged that the gases developed by combustion of the propellant charge are free to expand therein when the charge is ignited, the cross-sectional area of the throat of said gas discharge member being less than that of said barrel. Preferably the throat area or total throat area of the gas discharge member is less than the barrel bore area, but exceeds 50% of such area, so that escape of the gases through the discharge member will produce a substantially constant pressure in the chamber of the gun (comprising the cartridge and gas spaces) modified by the fall of pressure due to their gradual increase of chamber volume due to the movement of the projectile along the barrel.

It should be understood that in place of a single gas discharge member there may be several of such members and that it is immaterial to the invention in what direction the gases discharge from the gas outlet member or members, although in accordance with my concurrent application for Letters Patent filed September 1, 1944, Serial No. 552,347, they may be discharged rearwardly to reduce or eliminate recoil.

The gas escape member may have a throat area or total throat area which is substantially 66% of the barrel bore area, and preferably the gas discharge expansion nozzle has a throat area or total throat area which is substantially 66% of the barrel bore area.

It will be understood that the resistance of the projectile to movement along the barrel will have the effect of causing the bulk of the gases to discharge through the gas discharge nozzles, notwithstanding that their area is less than the barrel bore area.

The pressure within the breech chamber will be determined jointly by the rate at which the gases can escape through the barrel and gas discharge nozzles respectively, and the adiabatic expansion of the gases through the nozzles will produce a constant pressure in the chamber modified by the fall of pressure due to the gradual increase of the chamber volume due to the movement of the projectile along the barrel. Owing to the large volumes of gases which escape through the nozzles in comparison with the increase of chamber volume due to the travel of the projectile along the barrel, the passage of the projectile along the barrel will have a relatively very small effect on the chamber pressure in comparison with the effect due to the nozzles.

Thus, referring to Figure 10, the pressure B

in the chamber of the present invention will at first rise to a relatively low maximum, at a rate determined by the nature and method of ignition of the propellant charge until it reaches a substantially constant value, and thereafter it will fall at a relatively slow rate, so that the pressure curve will show, in comparison with the pressure curve A of a normal gun, that a substantially higher and more uniform mean pressure is maintained until the projectile leaves the gun muzzle. Since the work done on the projectile, which produces its velocity, is represented by the area beneath the pressure space curve, it follows that with a given length of gun the same velocity can be obtained as with a normal gun with a substantially lower maximum pressure. Furthermore, owing to the shape of the pressure space curve, any increase in the length of the barrel will result in a greater increase of work added, and therefore of velocity produced, than in the case of a normal gun in which the pressure falls off very rapidly towards the muzzle of the gun. Hence increase of the barrel length will be more advantageous in regard to the range or impact velocity obtainable than with a gun of normal construction, subject, of course, to the limiting conditions imposed by mechanical considerations.

As hereinbefore indicated the gases may be discharged through the expansion nozzle or nozzles in any desired direction, for example in relation to the axis of the barrel. However, if the expansion nozzle or nozzles is or are directed oppositely from the barrel, the gases discharging rearwardly therefrom at high velocity will produce a reaction in the forward direction, which will balance or partially balance the recoil of the gun to an extent dependent upon the bulk of gases allowed to escape through the rearwardly directed nozzle or nozzles. An adjustable valve device may be associated with the nozzle or nozzles whereby the throat area may be varied so that any desired proportion of the recoil may be absorbed up to a maximum of 100%, when the gun will be recoilless. If provision is made for restricting the nozzle area to an even greater extent the barrel may be given a forward motion instead of a backward recoil, which may in certain circumstances be advantageous for the operation of associated mechanism. However, it should be understood that the present invention is not concerned with modifying or eliminating the recoil of guns in the above manner, which forms the subject matter of my aforesaid concurrent application for Letters Patent Serial No. 552,347.

On the other hand it should be appreciated that since reduction of barrel weight is an object of this invention which is realised in part by the reduction of maximum pressure to a value little exceeding the mean pressure, the maximum advantage in this respect, viz. weight reduction, is obtained if the gun is also made recoil-less, since a direct result of this will be a further reduction in weight due to the elimination of the normal recoil mechanism.

Although in accordance with the foregoing the invention enables the thickness of the chamber wall and thus the weight of the gun to be reduced, the possibility of increasing the barrel length to maintain or increase the range or impact velocity without undue increase of weight is seriously limited by the "whippiness" and liability of thin barrels to bend under their own weight and thus produce inaccuracy of fire.

Consequently, in order to enable the advan-

5 tages of the main feature of the invention to be attained to the fullest extent, a further part of the invention consists in providing the gun with a thin barrel so constructed that its stiffness at right angles to its axis may be increased at all points along its length, without undue increase of weight.

10 It is a further object of the invention, therefore, to combine the improved breech with a thin barrel whose length can be increased without reducing its accuracy and yet without increasing its thickness.

15 According to this part of the invention, the gun comprises a breech portion as hereinbefore indicated in combination with a thin tubular barrel whose rigidity along its length is increased by a plurality of longitudinal ribs or webs, which decrease in depth progressively along the barrel, and are preferably spaced uniformly round the periphery of the barrel. In consequence, the 20 Moment of Inertia and thus the resistance to bending is increased at all points along the length of the barrel.

25 The edges of the ribs or webs may be straight and uniformly tapered from breech end to muzzle end. Also the edges of the ribs or webs may be flanged preferably on both sides of the webs, so that they are T-shaped in cross-section. The ribs or webs themselves may be straight, that is, run parallel to the axis of the barrel, or they may be helically arranged.

30 Preferably the barrel, with its longitudinal webs or ribs, is enclosed by an outer tube, which is preferably attached, as by screws, welding, or the like, to the edges or flanges of the ribs or webs.

35 In order that the invention may be more clearly understood and readily carried into practice it is illustrated by way of example only, in the accompanying drawings, in which:

40 Figure 1 is a side elevation of a 3.45", 25-pounder recoil-less field gun constructed in accordance with the invention.

45 Figure 2 is a plan view of the breech end of the gun with the breech open.

Figure 3 is a detail plan view of the breech chamber, to an enlarged scale, showing the ejector mechanism.

Figure 4 is a detail sectional view of one of the breech trunnions.

50 Figure 5 is a sectional view of the breech chamber adapted for use with a different form of breech mechanism.

Figure 6 is an enlarged detail sectional view of suitable firing mechanism.

55 Figure 7 is a half sectional view showing the improved construction of gun barrel according to the invention.

Figure 8 is a cross-section on line VIII—VIII of Figure 7.

60 Figure 9 is a cross-section on line IX—IX of Figure 7.

Figure 10 illustrates the pressure A obtained with a prior art gun as compared with the pressure B obtained with the gun of the present invention, and.

65 Figure 11 is a view corresponding to Figure 8 showing another breech chamber construction according to the invention for a gun not of recoil-less type.

70 The 3.25", 25-pounder gun illustrated by the drawings is mounted on wheels 70 and provided with the customary sighting equipment, and hand wheels 71, 72 for elevating and directing the barrel. It also carries a trail 73 to which the 75 breech end of the gun may be bolted at 74 for

transport purposes, the end of the trail 73 carrying a suitable coupling eye or hook 74a for towing purposes.

The gun in this case has a movable breech member 75 disposed between the gas chamber 76 and the gun barrel proper 77, which is rotatable about vertical trunnions 79 midway along its length. The portions of the trunnions—shown in detail in Figure 4—which are engaged with the breech member 75 consists of diametrical bars 78, and the said bars are formed by two telescopic parts, viz. a plunger and an outer casing, with a spring interposed between the parts, so as to make the bars 78 yielding as to their length, whereby a certain degree of longitudinal movement of the movable breech member 75 is permitted.

The breech member 75 is opened and closed by a handle 81 rotatable in brackets on the side of the breech member, and when the breech is closed the handle 81 occupies the position shown in dotted lines in Figure 2—i. e. pointing towards the rear end of the gun. On rotating the handle in a clockwise direction, its first movement rotates a small crank 82, and through a connecting rod 83, applies pressure to a locking pin 84 which bears on the end of the barrel. The consequent reaction shifts the breech member 75 rearwardly, which is permitted by the spring trunnion bars 78, thus causing positive disengagement of the breech member 75 from the gun bore. Further movement of the handle 81 carries the crank 82 past its dead centre position and withdraws the locking pin 84 from its hole in the end of the barrel, thus freeing the breech member 75 for rotary movement.

Continued movement of the handle 81 brings it up against a fixed abutment 85 (Figure 2) on the side of the breech member 75, whereupon this member rotates about its trunnions 79 into the position shown in full lines in Figure 2 and dotted lines in Figure 3.

During the initial rotation of the breech member 75 a cam 86 on the trunnion axis bears on the tail of the lever 87, and through rod 88 moves the pivoted extractor levers 89 through a small angle of 6°, thus loosening the cartridge case in the breech. As the breech member 75 swings into the fully open position the lever 87 strikes against a fixed stop 90, and the extractor is then moved a further 12° to throw the shell case out of the breech chamber.

The gas chamber 76 may be constructed internally in the same manner as the modified form of gas chamber 50 illustrated by Fig. 5, in which, instead of employing a swivelled breech member 75, as in Figures 1-4, the gas chamber has an interrupted screw thread engagement with the breech end of the barrel and can swing open angularly in a manner well-known in connection with guns. The method adopted for opening and closing the breech, however, forms no part of the present invention.

The gas chamber 50 corresponds to the gas chamber 76 of Figs. 1-4 and it can be assumed that the breech construction illustrated by Fig. 5 is applicable to the gun of Figs. 1-4, apart from the forward end of the gas chamber shown in Fig. 5, carrying the interrupted screw thread.

The gas chamber 50 (or 76) has a rear end wall fitted with a ring of fixed expansion nozzles 51 and a central adjustable nozzle 52, through which the gases escape rearwardly in relation to the direction of aim of the gun. Over the nozzle openings in the end wall is mounted a

perforated cone or grid member 53 which allows free passage of the gases to the nozzles, but holds back solid particles of propellant, and also defines a clear space through which the gases have access to the nozzle openings. Member 53 may be apertured in the manner indicated in Figure 11. At the forward end of the gas chamber 50 is disposed a spider ring 54 supporting a firing mechanism of the same type as that illustrated in detail in Fig. 6 as applied to the form of breech block shown in Figs. 1-4.

Supported by spider arms 55 over the inlet end of central nozzle 52 is a cone shaped valve member 56 which is aligned with the end of nozzle 52 and engages therein to a greater or less extent, according as the nozzle 52 is longitudinally adjusted by rotation in a bush in the end wall of chamber 50, with which it has a screw thread engagement. Thus the inlet or throat end of nozzle 52 is adjusted in regard to the stationary conical valve member so as to vary its effective throat area, thereby restricting the rate of escape of the gases and increasing the maximum pressure attained in the gas chamber 50. The nozzle 52 may thus be adjusted to cause the gun to be recoil-less or to have any desired proportion of its recoil absorbed. The setting of the nozzle may be indicated by calibrating the edge of the ring 57 on the nozzle and providing a fixed pointer on the chamber 59 to cooperate with the graduated edge of the ring.

The firing mechanism may be such as is illustrated by Figure 6. This figure shows the cartridge case 58 fitted into the breech member 75, with its base formed by a spider 59 flanged to engage the edge of the chamber, and supporting the percussion cap 60 for the primary charge, axially. The percussion cap 60 comes opposite to the centre portion 61 of spider ring 54, when the breech member 75 is in the closed position. The said centre portion 61 is hollow and contains the firing pin 62 slidable in a block 63 held in place by conical cover 64. The rear end of firing pin 62 is flanged and a spring 64' surrounds the firing pin and bears against the flange so as to withdraw the firing pin. Further forward the firing pin is slotted and in the slot is engaged a quadrant member 64'' which has trunnions 65 journaled in centre portion 61. One radial edge 45 of the quadrant 64'' is adapted to bear on the end of the slot in the firing pin, whilst the other radial edge comes beneath a hole in one of the spider arms 54 through which passes the primary striking pin 66. By striking the outer end of pin 66, as by means of a pivoted hammer 67, an impulse is transmitted to quadrant 64'' which is transferred to the firing pin 62 and drives it forwardly against the percussion cap 60, after which it is withdrawn again by the spring 64'.

It will be understood that the guns of Figures 1-6 are provided with rearwardly directed gas nozzles, so as to be of recoil-less type. The invention may be carried out, however, without the aid of the recoil-less principle by directing the gas escape nozzles 51a in directions other than rearwardly, for example, laterally as in Figure 11, the throats of the nozzles 51a being covered with conical grids 53a corresponding to the grid 53 of Figure 5.

The preferred construction of gun barrel for constant pressure guns according to the invention is illustrated particularly by Figures 7, 8 and 9.

The gun barrel proper 77 consists of a relatively thin walled tube 68 of uniform thickness

adequate to withstand the maximum pressure of the chamber gases. This is surrounded near its breech end by an annular fitting comprising an inner sleeve 69 encircling the barrel 68, and spaced therefrom an outer sleeve 170, forming flanges on both sides of an apertured web 171 connecting together the two sleeves 69 and 170. From the annular fitting extend forwardly along the barrel a plurality of ribs or webs 172 which radiate from the axis of the barrel and are spaced symmetrically around the barrel. These webs 172 gradually decrease in depth from breech to muzzle, and they may also if desired decrease in thickness. The decrease in depth may be uniform, so as to produce a straight line edge, or the decrease in depth may vary in accordance with a parabolic law. The outer edges of the ribs or webs 172 are preferably flanged on both sides, as shown, and their inner edges are welded to the barrel tube 68 at intervals or continuously along their length.

The ribs or webs 172 are enclosed by an outer tapering tube 173 preferably attached, as by screws, welding or the like, to the flanged edges of the ribs or webs. The breech end of tube 173 is fitted on and secured to the outer sleeve 170 of the annular breech fitting, and at its muzzle end the tube is attached to a ring 174 encircling the muzzle end of tube 68.

The annular fitting 69, 170, 171 also carries the trunnions 175 for supporting the gun barrel assembly, and in addition to the forwardly extending ribs 172, is provided with short rearwardly extending tapered webs or ribs 176 extending to the screw thread 177 by which the barrel assembly is screwed into the breech structure of the gun. These webs or ribs 176 may be enclosed in a conical sleeve or cover tube fitted on to the rearward flange formed by sleeve 170.

It will be appreciated that the ribs or webs 172 will greatly increase the moment of inertia, and thus the resistance to bending of the barrel as a whole, without unduly increasing its weight in comparison with the increase of weight which would result from increasing the thickness of the barrel tube 68 in order to obtain an equal resistance to bending, which would negative the saving in barrel weight due to the reduction in the maximum chamber pressure obtained as a result of the invention.

For reasons of stability of the projectile, particularly when self propelled or rocket projectiles are used, it may be desirable to destroy the pressure of the gases on the base of the projectile before it leaves the muzzle. To achieve this end the muzzle portion of the barrel tube 68 may be perforated as shown at 180 in Figure 7, for a suitable length, so as to allow lateral escape of the gases into the interior of the outer casing 173, in which case the annular muzzle ring 174 would be perforated, as shown at 181 in Figure 8, to allow the gases to escape into the atmosphere. With such a construction the barrel perforations may be of a total area equal to four times the area of the barrel bore, and the area of the annular space between barrel 68 and outer casing 173 may be twice said barrel bore area. The sudden increase of the barrel volume when the projectile passes the perforations will cause a sudden drop in the chamber pressure, to such an extent that the combustion of the propellant is reduced in speed or even brought to an end before the charge is fully burnt, so that the pressure acting on the base of the projectile on leav-

ing the muzzle is much reduced or is entirely eliminated.

This invention is distinguished from that of my prior but concurrent application for Letters Patent, Serial No. 552,347, in that the gases discharged from the breech chamber may be discharged in any desired direction in the case of the present invention, whereas in the case of my said prior application the gases must be discharged in the rearward direction so as partially or wholly to eliminate recoil of the gun. Thus the prior application relates to a particular case of the present invention i. e. rearward discharge of the gases, when the additional advantage mentioned above is obtained.

15 I claim:

1. A gun comprising a barrel having a projectile-receiving portion at its rear end, a breech chamber including a cartridge space secured to the rear end of the barrel to receive an explosive propellant charge when the gun is loaded, the wall of the breech chamber supporting a gas discharge member having a restricted throat and an outlet opening to the atmosphere, part of said breech chamber forward of rear wall thereof and additional to the cartridge space forming a gas space of substantial volume in direct communication with both the cartridge space and the throat of said gas discharge member, said cartridge space having a venting area into the gas space at least equal to the cross-sectional area of the barrel, and said gas space being so constructed and arranged that the gases developed by combustion of the propellant charge are free to expand therein when the charge is ignited, the cross-sectional area of the throat of said gas discharge member being less than that of said barrel.

2. A gun according to claim 1, wherein the barrel of the gun is made of relatively thin metal and is stiffened against bending by longitudinal external ribs decreasing in depth from the barrel breech towards the barrel muzzle.

3. A gun according to claim 2 wherein the outer edges of the ribs are flanged.

4. A gun according to claim 2 wherein the longitudinal ribs extend parallel to the muzzle axis.

5. A gun according to claim 2 wherein the gun barrel is enclosed in an outer tube positioned concentrically with the barrel and spaced from the barrel by said ribs.

6. A gun according to claim 1 wherein the gun barrel has an outer wall spaced from an inner wall to form a chamber between said inner and outer walls, the inner wall being provided with apertures adjacent the gun muzzle placing the bore into communication with the annular space between the inner and outer walls, and means to place said annular space into communication with the atmosphere.

7. A gun according to claim 1, wherein the throat area of the gas discharge member is substantially 66% of the barrel bore area.

8. A gun according to claim 1, wherein the gas discharge member is a conical expansion nozzle.

9. A gun according to claim 1, wherein an adjustable means is provided to reduce the size of the throat of the gas discharge member.

10. A gun according to claim 1, including a ring member associated with the throat of the gas discharge member, and a conical expansion nozzle adjustably movable with respect to the opening in said ring member, whereby the effec-

tive area of the ring member opening may be reduced.

11. A gun according to claim 1, wherein the breech chamber gas space is provided with a perforated element positioned between the cartridge space and the gas discharge member. 5
